UNITED STATES PATENT OFFICE.

ERNST NÄGELIN, OF BASEL, SWITZERLAND.

HOLDING APPARATUS FOR THE WET TREATMENT OF FABRIC IN WEB FORM.

Application filed April 14, 1924. Serial No. 706,612.

To all whom it may concern:

Be it known that I, ERNST NÄGELIN, a citizen of the Swiss Republic, and resident of Basel, Switzerland, have invented new and useful Improvements in Holding Apparatus for the Wet Treatment of Fabric in Web Form, of which the following is a full, clear, and exact specification.

This invention relates to holding apparatus especially for wet treatment of fabric in web or strip form, in which the suspended and folded fabric is dipped into the bath or otherwise treated.

In known apparatus of this kind the fabric sheets, layers or folds are for the most part continuously and directly fastened individually to hooks or pins, in which case the piercing is mostly at the two fabric edges, but sometimes only at one web edge in suspension. Usually in the latter case it is necessary to provide the fabric web with protecting edges, in order to avoid damaging the fabric by the hooks and on the other hand to prevent direct contact of the fabric to be treated with the hanging hooks or pins, since this involves slight chemical action at the points of contact which is harmful to the fabric. Further, in wet treatment the free access of the bath especially to the points of suspension is hindered owing to the compression thereof resulting from the pull of the fabric caused by the suspension.

In the holding apparatus according to the invention, in which the fabric is likewise continuously hung up in suspension on carrying hooks, these disadvantages are avoided. In this case the suspension of the fabric on each row of carrying hooks is effected by one of a series of tightly tensioned threads which are drawn through the individual layers of the fabric and are carried in the rows of hooks which project between them so that the suspension of the fabric on the hooks is effected without the aid of protecting borders and the treatment of the material can take place all over simultaneously.

An embodiment of the invention is shown by way of example in the accompanying drawings.

Figure 1 is a perspective view.

Figure 2 is a side view, and

Figure 3 is a cross section of a suspension rake.

The continuous folds of the fabric in this case lie round one another in spiral form; they can, however, also lie adjacent to one another in serpentine form. The single layers of fabric are held in three, four or more places by means of threads *a* which are drawn through the single layers of the suspended fabric. By means of these different threads *a* the fabric is hung on the downwardly directed hooks *b* of the members *c*, so that the threads or laces *a* are carried in the ends of the hooks *b* between each layer of fabric and are drawn tight by tensioning over the side pieces *f* of the hanging members. The members *c* themselves can be taken out or adjusted in the slotted supporting guides *d*, and these supporting guides *d* are adjustably situated on cross supports *e*, which are carried in any convenient manner by a raising mechanism, for the sake of simplicity not shown, so that the fabric can be dipped in the bath or removed therefrom.

In the above described suspension the folds of the fabric cannot or can only loosely come into contact with one another, being kept separated singly or in twos or threes between the hooks *b*. The bath can thus freely reach the material at these places, so that uniform treatment therefore takes place.

Further, hanging of the fabric on the hooks is facilitated without the fabric itself being hooked and thereby damaged, whilst the threading of the suspended fabric can be effected quickly and without damage.

What I claim is:

1. A holding apparatus for the wet treatment of fabric in web form, and folded into layers comprising a row of carrying hooks and a tightly tensioned thread arranged to be drawn through the individual layers of the web and to be laid into said carrying hooks between said layers, for the purpose specified.
2. A holding apparatus for the wet treat-

ment of fabric in web form, and folded into layers comprising a plurality of rows of carrying hooks, a movable support therefor and a plurality of tightly tensioned threads arranged to be drawn through the individual layers of the web and to be laid into said carrying hooks between said layers, for the purpose specified.

In witness whereof I have hereunto signed my name this 28th day of March, 1924, in ¹⁰ the presence of two subscribing witnesses.

ERNST NÄGELIN.
